US00D764426S

(12) **United States Design Patent**
Kwak et al.

(10) **Patent No.:** **US D764,426 S**
(45) **Date of Patent:** **** Aug. 23, 2016**

(54) **ELECTRONIC DEVICE**

(71) Applicant: **Samsung Electronics Co., Ltd.,**
Suwon-si (KR)

(72) Inventors: **Ji-Yeon Kwak**, Seoul (KR); **Kio Lee**,
Seoul (KR); **Hyun-Jin Kim**, Seoul (KR)

(73) Assignee: **SAMSUNG ELECTRONICS CO., LTD. (KR)**

(**) Term: **14 Years**

(21) Appl. No.: **29/487,406**

(22) Filed: **Apr. 8, 2014**

(30) **Foreign Application Priority Data**

Oct. 10, 2013 (KR) 30-2013-0051310

CLAIM

We claim, the ornamental design for an electronic device, as shown and described.

DESCRIPTION

FIG. 1 is a perspective view of an electronic device, showing our new design;

FIG. 2 is a front elevation view thereof;

FIG. 3 is a rear elevation view thereof;

FIG. 4 is a side elevation view thereof;

FIG. 5 is another side elevation view thereof;

FIG. 6 is a top plan view thereof; and,

FIG. 7 is a bottom plan view thereof.

The broken lines illustrating portions of the electronic device are for environmental purposes only and form no part of the claimed design.

1 Claim, 7 Drawing Sheets
